Primary Examiner—Bernard Ansher

[57] CLAIM

The ornamental design for an arm-sling, substantially as shown and described.

DESCRIPTION

FIG. 1 is a front elevation of an arm sling, showing our new design;

FIG. 2 is a rear elevation thereof;

FIG. 3 is a front perspective thereof;

FIG. 4 is a rear perspective thereof;

FIG. 5 is a front elevation of a second modified embodiment of the arm-sling illustrated in FIG. 1;

FIG. 6 is a rear elevation thereof;

FIG. 7 is a front perspective thereof;

FIG. 8 is a rear perspective thereof;

FIG. 9 is a front elevation of a third modified embodiment of the arm-sling illustrated in FIG. 1;

FIG. 10 is a rear elevation thereof;

FIG. 11 is a front perspective thereof;

FIG. 12 is a rear perspective;

FIG. 13 is a front elevation of a fourth modified embodiment of the arm-sling illustrated in FIG. 1;

FIG. 14 is a rear elevation thereof;

FIG. 15 is a front perspective thereof;

FIG. 16 is a rear perspective thereof; and

FIG. 17 is an enlarged fragmentary elevation of the ornamental pattern depicted in FIGS. 13-16, inclusive.
